UNITED STATES PATENT OFFICE.

ARCHER W. RICHARDS, OF LAKWOOD, OHIO, ASSIGNOR, BY MESNE ASSIGNMENTS, TO THE FIRESTONE STEEL PRODUCTS COMPANY, OF AKRON, OHIO, A CORPORATION OF OHIO.

CLAMPING MECHANISM FOR WELDERS.

1,274,451.

Specification of Letters Patent.

Patented Aug. 6, 1918.

Application filed May 18, 1917. Serial No. 169,439.

To all whom it may concern:

Be it known that I, ARCHER W. RICHARDS, a citizen of the United States, residing at Lakewood, in the county of Cuyahoga, State 5 of Ohio, have invented certain new and useful Improvements in Clamping Mechanism for Welders, as shown in the accompanying specification.

This invention is directed to an attachment for use on electric welders, or similar apparatus, designed to replace the heavy manually-operable clamps at present in use on this type of machine, and to quickly and accurately clamp ends of metal in abutment 10 for the operation known as butt-welding. It is particularly designed for butt-welding the ends of rims, felly bands or the like parts for the manufacture of demountable automobile rims, although it is not intended 15 to be confined to this class of work.

In the drawings accompanying this application is shown one form of the device embodying my invention, in which

Figure 1 is a side elevation of an electric welder with the clamping mechanism mounted thereon, the clamping mechanism being shown in section, with clamps withdrawn and a portion of the rim mounted on the welder.

Fig. 2 is a similar view of my attachment showing the mechanism in extended or clamping position.

Fig. 3 is a front elevation of the clamping attachment, the left hand half being shown 35 in section with the clamping shoe removed.

The welder is indicated as a whole by the numeral 1 and is of any well known type, the platen being designated by the numeral 2. The clamping mechanism is carried in 40 the platen and comprises two similar mechanisms placed in juxtaposition, one right-hand and one left-hand, the construction being the same except for a reversal of parts. Each mechanism comprises a bracket or 45 housing 4, which is secured to the platen 2 by a forwardly extending arm 5 on the end of which is secured a rest 6 for the work, here shown as a rim base 7.

On the upper rear corner of each housing 50 is secured a cylinder 8 in which is mounted for reciprocation a piston 9. This cylinder is intended to be connected with a source of fluid pressure, air or water, by means of pipes 10 arranged to afford inlet or outlet 55 means for operation of the piston as will be

readily understood. A link 11 is connected to the piston 9 at one end, the other end being pivotally connected to the knee of a toggle formed by levers 12 and 13.

The lever 12 is pivoted on a transverse rod 60 14 mounted in the upper end of the casing 4, and the lever 13 is pivotally connected to a web 15 formed on the upper side of the movable clamping arm 16. The housing 4 is open to permit the reciprocation of the 65 clamping arm and its outer side wall supports, by means of bolts 17, a guide rail 18 formed with an enlarged head 19.

A rearward extension 20 is formed in the arm 16 which is provided with a longitudinal slot 21. A roller 22 mounted on a shaft 23 is received in this slot and supports the rear end of the arm. The outer face of each arm 16 is provided with a longitudinal groove or track 24 in which is received the 75 head 19 of the guide rail plates 25 and 26 being secured to the arm serving to hold it on the rail. The upper plate 25 is cut back in its rear portion as at 27 to enable the clamping arm to drop on the work as will appear in the description of the operation of the apparatus. To the front inner face of each clamping arm is fastened a shoe 28 the under side of which has a hardened face 29 adapted to come directly over the work 80 rest 6, and provided with recesses 31 to receive ribs or other irregularities on the rim. Adjusting screws 30 are carried in the clamping arms and bears against the upper 85 surface of the shoes.

A rim section, or other part, being ready for welding the ends are placed in abutment on the work rests 6 and the valves opened admitting fluid pressure on the rear of the pistons 8. The clamping arms 16 are then moved forward horizontally until recessed portion 27 of the plates 25 registers with the rails 19. At the same time the roller 22 reaches the end of the slot 21. Continued movement of the piston straightens out the 90 toggle 12-13 and the arm 16 rocks on the roller, bringing the clamping shoe down firmly on the ends of the work. When the welding is completed the piston is withdrawn the clamping arm rising up from the 95 work in a straight line until the rail 19 strikes the lower plate 26, whereupon the arm will be withdrawn to its original position.

In placing the rim or other material in 100

position to be clamped and welded it is often necessary for the operator to hold the ends together until they are clamped as they may be sprung out of line. Were an ordinary swinging clamp used for this work, it would be very dangerous as the workman's hand could be caught before he had a chance to withdraw it. With the arrangement here shown the lateral motion of the clamping arm, passing as it does but a slight distance over the upper surface of the rim, will serve to push the hand of the operator off the rim before the clamp descends.

It is obvious that various changes and modifications may be made in the construction of the clamping mechanism, without departing from the spirit of the invention, it being essential that the clamp be moved horizontally over to a point above its clamping position and then downwardly on to the work. This may be done by a system of levers other than that shown or by the use of separate cylinders to perform the two movements.

25 What I claim is:

1. In combination with an electric welder, a clamping arm adapted to hold the work, and means to move said clamping arm in one direction over the work, and in another direction to clamping position.
2. In combination with an electric welder, a clamping arm adapted to hold the work and means to move said clamping arm laterally, to a position over the work, and vertically to clamping position.
3. In combination with an electric welder, a clamping arm, a support for said arm adapted to guide it for horizontal movement

to clamping position and release it for clamping.

4. In combination with an electric welder, a clamping arm, means to guide said arm horizontally to clamping position and to release it for vertical movement for clamping, and lever mechanism to move it horizontally and vertically.

5. In combination with an electric welder, a clamping arm, means to guide said arm horizontally to clamping position and to release it for vertical movement for clamping, a toggle joint connected to said arm and adapted to move it horizontally and vertically.

6. A clamping mechanism for an electric welder comprising a bracket on said welder, a clamping arm, a rail on said bracket to support the clamping arm for horizontal movement, the body of the arm being provided with a slot, a shaft in said bracket passing through said slot, and adapted to form a pivotal support for the arm in its vertical movement.

7. A clamping mechanism for an electric welder, comprising a bracket on said welder, a clamping arm capable of both horizontal and vertical movement, a rail on said bracket to support the clamping arm for horizontal movement, a shaft passing through the arm and adapted to form a pivot for the vertical movement of the arm, a toggle lever connected to said bracket and said arm, and a fluid actuated mechanism for operating said toggle to move the clamping arm both horizontally and vertically.

ARCHER W. RICHARDS.
